Attorney

UNITED STATES PATENT OFFICE.

FRANK B. BARSTOW, OF REHOBOTH, MASSACHUSETTS.

CIGARETTE FORMER.

Application filed February 24, 1925. Serial No. 11,055.

To all whom it may concern:

Be it known that I, FRANK B. BARSTOW, a citizen of the United States, residing at Rehoboth, in the county of Bristol and State 5 of Massachusetts, have invented new and useful Improvements in Cigarette Formers, of which the following is a specification.

This invention relates to certain new and useful improvements in cigarette formers, 10 and the primary object thereof is to provide a cigarette former which has improved means for uniformly feeding and packing the tobacco in the paper wrapper.

A further object of the invention is to provide packing means which can be easily manipulated, which is of simple construction and which can be economically produced.

A still further object of the invention is 20 to provide packing means which acts to gradually move the cigarette away from the former as the packing progresses until completion, when the cigarette is entirely disengaged.

25 In the drawings:—

Fig. 1 is a longitudinal sectional view of the invention;

Figure 2 is a top plan view and

30 Figure 3 is a sectional view on line 3—3 of Fig. 1.

In proceeding in accordance with the present invention, a tube 1 is employed of a diameter and length equaling that of the cigarette to be rolled. A funnel or hopper 35 2 is connected to one end of the tube.

The plunger or packing element is of spiral formation and is preferably constructed of a pair of wires 6 and 7 which latter are bent at one end into circular or 40 hoop formation at 8 and 9 and are disposed with the sides of the loops conjointly forming a handle or finger grip. The wires are twisted into engagement with each other to 45 form a spiral shank and have their free extremities 4 and 5 divergently related to form a pair of angularly related spreading or agitating fingers.

In operation, the paper wrapper W is wound about the exterior of the tube 1 and its outer end twisted at W to close same 50 against the egress of the tobacco. The tobacco is now placed in the funnel or hopper, whereupon the plunger is placed in the tube and moved inwardly and outwardly and rotated, the plunger due to its spiral formation 55 causing the tobacco to move downwardly, the agitating fingers effecting even or uniform packing of the tobacco and at the same time the cigarette is gradually moved off of the tube until upon completion, it is entirely 60 disengaged.

From the above it will be seen that the tobacco is fed and packed gradually and uniformly and the cigarette is moved away 65 from the forming tube as completed until finally completed when the cigarette is entirely moved out of engagement with the forming tube or cylinder.

Having thus described my invention, what I claim as new and desire to secure by 70 Letters Patent is:—

1. In a cigarette former, a hollow forming member adapted to receive the cigarette wrapper thereon, and a plunger receivable in the member and composed of two wire strands twisted together to provide a spiral formation, the strands at one end having abutting loops conjointly forming a handle and having opposite ends free and divergently related to form angular agitating fingers.

2. In a cigarette former, a hollow forming member adapted to receive the cigarette wrapper thereon, and a plunger in the member composed of wire twisted to form a spiral shank and having the ends of the wire free and extended outwardly to form agitating fingers.

In testimony whereof I have signed my name to this specification.

FRANK B. BARSTOW,
